[57] CLAIM

The ornamental design for a combined coupon holder, writing instrument and memo pad, as shown and described.

DESCRIPTION

FIG. 1 is a top plan view of a combined coupon holder, writing instrument and memo pad showing my new design;

FIG. 2 is a bottom plan view thereof;

FIG. 3 is a front edge elevational view;

FIG. 4 is a rear edge elevational view;

FIG. 5 is a left edge elevational view;

FIG. 6 is a right edge elevational view;

FIG. 7 is an enlarged scale fragmentary cross-sectional view taken along line 7—7 of FIG. 1;

FIG. 8 is an enlarged scale fragmentary cross-sectional view taken along line 8—8 of FIG. 1; and

FIG. 9 is a perspective view of the combined coupon holder, writing instrument and memo pad shown in a closed condition.
